UNITED STATES PATENT OFFICE

2,603,070

REFRIGERATED TRANSPORTATION UNIT

Forrest E. Gilmore, Bartlesville, Okla., assignor,
by mesne assignments, to Frigid Transport
Company, Inc., New York, N. Y., a corporation
of New York

Application August 18, 1945, Serial No. 611,365

6 Claims. (Cl. 62—5)

1

This invention relates to refrigerated transportation units.

The invention is shown herein as applied to an automotive truck, but it is apparent that the same principles may be applied to other forms of transportation units and certain items are useful in refrigerated systems generally.

In the transportation unit of the present invention, the cooling element is a portion of an absorption refrigeration system contained in an insulated body and the unit has mounted thereon one or more absorbent holders for collecting the vaporized refrigerant. The remaining elements of an absorption system, namely, the generator, the dehydrator, the condenser and the storage tanks for the liquid refrigerant and the weak and strong liquors are located at a central station at which the units are serviced.

Each central station serves a large number of transportation units. As each transportation unit enters a central station, the absorbers are emptied of their charge of strong liquor, the evaporator is recharged with refrigerant and the absorbers are recharged with weak liquor or absorbent whereupon the transportation unit is ready to resume its travel with full refrigeration capacity. The transportation unit may be designed for twenty-four-hour or longer service without recharging at the will of the designer.

The present application is directed to numerous features making for the economical construction and operation of the transportation unit, the efficient operation of the refrigeration system and the efficient and easy emptying and recharging of the transportation unit.

One object of the invention is to provide a transportation unit wherein there are two cooling compartments which are accessible independently of the other.

Another object of my invention is to provide an arrangement whereby the operation of the cooling unit is controllable by the operator from the outside of the insulating body.

Still another object of the invention is to provide in a transportation unit of the above-identified character, arrangements whereby the refrigeration elements therein may be emptied and charged at will without opening the insulated body.

A further object of the invention is to provide an improved arrangement for insuring complete saturation of the spent absorbent by the refrigerant.

A still further object of the invention is a novel arrangement of absorbers and connections there-

2

between and to the evaporator to insure efficient operation of the system.

Other objects, novel features and advantages of this invention will become apparent from the following specification and accompanying drawings, wherein:

Fig. 1 is a vertical section through a transportation unit embodying the invention;

Fig. 2 is a plan view of the cooling apparatus;

Fig. 3 is a section on the line 3—3 of Fig. 1;

Fig. 4 is a diagrammatic view of the cooling apparatus;

Fig. 5 is a fragmentary enlarged section through one absorbent holder;

Fig. 6 is a view similar to Fig. 5 through another absorbent holder;

Fig. 7 is a fragmentary enlarged section through the refrigerant holder;

Fig. 8 is an elevation of the connection for use in filling or emptying the absorbent holder;

Fig. 9 is a section on the line 9—9 of Fig. 8;

Fig. 10 is a plan view of the connection for use in charging the refrigerant holder;

Fig. 11 is a section on the line 11—11 of Fig. 10;

Fig. 12 is a partially diagrammatic view of a modification, and

Fig. 13 is a section on the line 13—13 of Fig. 12.

In the embodiment herein shown, a suitably insulated body or enclosure 10 is supported by the chassis of an automobile truck having an operator's cab mounted forward of the body. A generally cylindrical tank 11 is supported horizontally near the top of the enclosure 10 transversely thereof. A pipe 12 communicates at one end with a cylindrical housing 13 vertically supported within the tank 11 near the top thereof and contains a valve seat 14 for co-operation with a ball valve 15 to control flow into the tank 11 (Fig. 7). The remaining end of the pipe 12 communicates with a coupling member 16 carried by the body 10 (Figs. 1 and 10).

Two pairs of headers 17 and 18 depend from the tank 11 in communication therewith and each pair of headers supports a plurality of transversely arranged horizontal pipes 19 having finned cooling surfaces 20. Each header 17 extends nearly to the top of the tank 11 whereas each header 18 terminates flush with the inner surface of said tank. The tank 11, together with the headers and finned pipes constitute the evaporator of an absorption refrigerating system (Figs. 1, 3 and 4).

A vertical plate 21 of the same width as the body 10 is located between the two sets of pipes

19 and may extend to the floor of the body to divide the body into two compartments for which suitable doors may be provided. In the plate 21 is provided an opening 22 which receives a horizontal tray 23 arranged below the pipes 19 for the purpose of collecting drippings from said pipes. A drainage pipe 24 leads from the tray 23 to a point below the bottom of the body.

Two generally cylindrical tanks 25 and 26 having valve-controlled vents 25a and 26a are horizontally supported beneath the body 10 longitudinally thereof in position to be contacted by the stream of air flowing beneath the body upon forward movement of the vehicle and constitutes the absorbent holder for the refrigerating system. A pipe 27 leads to the tank 25 from a coupling member 28 supported by the vehicle and terminates near the bottom of the tank 25. A pipe 29 leads from the top of the tank 11 to one end of a tubular casing 30 in the bottom of the tank 25 and having at its other end a conical discharge nozzle 30a enclosed by a boss 30b having a lateral port 30c beyond the nozzle end communicating with one end of an upwardly inclined pipe 31 within the tank 25. In the pipe 29 there is provided a manually adjustable back pressure regulating valve 32 and a manually operated valve 32a upstream of the valve 32 while a pipe 33 leads from the pipe 29 at a point between the valve 32a and the tank 11 to a pressure gage 34 arranged on the outside of the front wall of the body 10 in a position to be readily visible to the truck operator. A pipe 35 leads from a point near the top of the tank 25 into the bottom of the tank 26 and communicates with a tubular casing 36 intermediate its ends. The casing 36 has a conical discharge nozzle 36a enclosed by a boss 36b having a port 36c beyond the nozzle end and communicating with one end of an upwardly inclined pipe 37 within the tank 26. At the other end of the casing 36 there is provided a downwardly extending tube 38 terminating near the bottom of the tank 26 and containing a ball check valve 39 arranged to permit inflow only. A pipe 40 controlled by a manually operated valve 41 leads to the tank 26 from the pipe 29 at a point between the valve 32 and the tank 11.

The tank 11 is supported from the ceiling by a frame 42 which also supports a pair of plates 43 and 44 of substantially the same width as the body 10 exterior of the coils 19. The space above and below the coils 19 between the partition 21 and the plates 43 and 44 is open so as to provide a chimney effect with respect to each coil for circulating the air in each compartment over a coil.

A float 45 is carried by a forked arm 46 which is mounted on a cross-pin 47 free to rotate in registering holes in the casing 13. A cam 48 is adjustably fastened on the pin 47 by means of a set screw 49 and underlies the valve seat 14 in position to project through said seat sufficiently to engage the ball valve 15 to lift it from its seat. The cam 48 is provided with a depression 50 to receive the ball 15 in one position of the cam 48 to permit the ball to fit the seat 14 to prevent inflow through the casing 13. An adjustable counterweight 51 is mounted on the arm 46 opposite the float 45. The cam 48 is adjusted on the pin 47 so that the recess 50 is in position to receive the ball 15 when the liquid in the tank 11 has reached the desired level and prevent further inflow.

To prepare the system for operation, anhydrous ammonia is introduced into the tank 11 by means subsequently to be described through the coupling

member 16, pipe 12 and housing 13 until a predetermined depth of liquid refrigerant has been obtained in the tank whereupon the valve 15 seats to prevent further flow to the tank. Weak liquor is introduced into the absorbers 25 and 26 by means subsequently to be described through the coupling member 28, pipe 27 and pipe 35. The tank 25 first fills up to the level of the top of the pipe 35, after which the weak liquor flows through the pipe 35 into the tank 26 through casing 36. Flow is continued until the desired level of liquid is attained in the tank 26. When both tanks 25 and 26 are filled, liquid is contained within the pipes 31 and 37 to the full extent thereof.

During operation, anhydrous ammonia flows from the tank 11 through the headers 18 into the pipes 19 in which it is vaporized, thereby taking up heat from the enclosure to lower its temperature. The vaporized refrigerant flows through the headers 17 to the tank 11 from which it is discharged through the pipe 29 and valves 32a and 32 into the casing 30 from which it flows through the pipe 31 in which it is thoroughly contacted with the liquid therein to promote absorption of the vaporized refrigerant by the weak liquor in the tank. When the liquid in the tank 25 has lost its absorptive capacity, additional vaporized refrigerant introduced into the tank 25 passes from the tank through the pipe 35 into the tank 26 by way of the casing 36 and pipe 37. The vaporized refrigerant thus introduced into the tank 26 is thoroughly contacted with the liquid in the tank to promote absorption of the ammonia vapor by the weak liquor contained in the tank.

After a period of operation, both tanks 25 and 26 are drained and fresh weak liquor is introduced. In draining, the coupling member 28 is connected to a suitable suction source and liquid is drained through the pipe 27 from the tank 25. As liquid is withdrawn from the tank 25, it is replenished by liquid flowing from the chamber 26 under the influence of the greater pressure existing in the tank 26. Liquid flows from the tank 26 by way of the inlet 38 into the casing 36 from whence it flows through the pipe 35 into the tank 25 which remains full until the tank 26 is empty. The discharge of liquid from the tanks may be facilitated by opening the valve 41, thereby supplying to the liquid in the tank 26 the pressure existing in the tank 11.

As shown in Figs. 8 and 9, the coupling 28 comprises a housing 52 communicating with the pipe 27 and provided at one end with a valve seat 53 which is adapted to receive a ball valve 54 contained in the housing. A helical spring 55 carries a spider 56 for engagement with the ball 54 to bias the ball into engagement with the seat 53. A second coupling member 57 comprises a tubular housing having a port 58. Quick detachable means 59 of any suitable construction and having an actuating hand wheel 60 are provided for clamping the two coupling members 28 and 27 together with their opposing faces in liquid-tight contact. A stem 61 is rotatably supported within the coupling 57 with a portion extending exteriorly of the casing and to which a hand wheel 62 is attached. A threaded portion of the stem 61 engages a feed nut 63 mounted within the casing so that rotation of the stem produces axial movement thereof. The stem 61 has a head 64 for engagement with the ball 54. A flexible hose 65 is connected to the port 58 and leads to a source of weak liquor. With the coupling 57 disengaged from the coupling member 28, the ball 54 automatically seats to close the passageway through

the coupling 28 and prevent escape of liquid from the tank 25.

As shown in Figs. 10 and 11, the coupling member 16 consists of a housing 70 having a valve seat 71 at one end thereof. A valve 72 is mounted in the housing for movement toward and away from the valve seat 71 and has a threaded bore into which extends the threaded portion of a stem 73 having one end exterior of the housing and equipped with a hand wheel 74. A collar 75 on the stem 73 prevents axial movement of the stem 73. A second coupling member 16 for co-operation with the coupling member 16 consists of a housing 76 having a frusto-conical valve seat 77 at one end. A stem 78 is rotatably supported within the housing 76 by a feed nut 79 having engagement with a threaded portion of the stem 78 whereby axial movement of the stem is effected upon rotation thereof. At one end, the stem is equipped with a frusto-conical valve 80 adapted to engage the seat 77 and at its opposite end is provided with a hand wheel 81 exterior of the casing. Quick detachable means 82 of any suitable construction and having an actuating hand wheel 83 are provided for connecting together the two coupling members with their opposing ends in contact and with the outer faces of the valve 72 and 80 in contact. The casing 70 is connected to the pipe 12 while the casing 76 is connected to a flexible hose 84 connected to a source of liquid anhydrous ammonia. Normally, the valve 72 engages the valve seat 71 to prevent escape of refrigerant from the tank 11.

When it is desired to charge the tank 11 with anhydrous ammonia, the casing 76 is connected to the casing 70 as shown in Figs. 10 and 11 with the valves 72 and 80 engaging the valve seats 71 and 77 respectively. The hand wheels 74 and 81 are then rotated to retract the valves from their valve seats to permit the flow of anhydrous ammonia from the hose 84 through the casings 76 and 70 into the pipe 12. After the tank 11 has been charged, the hand wheels 74 and 81 are rotated to engage the valves with their valve seats, after which the casing 76 is disconnected from the casing 70. The arrangement of valves 72 and 80 with their outer faces in engagement when both are seated, prevents any loss of anhydrous ammonia during charging.

When it is desired to charge the tanks 25 and 26 with weak liquor, the coupling member 57 is attached to the coupling 28 as shown in Figs. 8 and 9 with the head 64 in its retracted position. The hand wheel 62 is then operated to disengage the ball 54 from its seat 53 against the action of the spring 55, thereby permitting influx of weak liquid from the hose 65 through the port 58 around the head 64 and ball 54 into the housing 52 and thence through the pipe 27. After the tanks 25 and 26 have been charged with weak liquor to the desired depth, the hand wheel 62 is rotated to retract the head 64 and permit the ball 54 again to engage its seat 53. Upon disengagement of the coupling member 57 from the coupling member 28, the only loss of weak liquor is that contained in the small space between the exposed surface of the ball 54 and the adjacent end of the coupling member 57.

Instead of a float-controlled valve in the tank 11, flow of anhydrous ammonia thereto may be regulated by the arrangement illustrated in Figs. 12 and 13. In this arrangement, a non-magnetic metal cup 85 is screwed into a threaded boss 86 provided in the wall of the tank 11. The

end of the cup 85 is closed by a second non-magnetic metal cup 87 having threaded engagement with the rim of the cup 85. The cup 85 rotatably supports a shaft 88 to which is attached an arm 89 carrying a float 90 at its outer end. A permanent bar magnet 91 is carried by the shaft 88 within the cup 85 and a pointer 92 of magnetic metal is rotatably supported by the bottom of the cup 87 to which it is electrically connected. The cup 87 supports an insulated stationary contact 93 in position to be engaged by one end of the pointer 92. A conductor 94 leads from the contact 93 to the positive pole of a battery 95. A pipe 96 provided with a self-closing magnetic valve 97 and with a meter 98 is connected to the hose 84 leading to the coupling member 76. One terminal of the magnetic valve 97 is connected through the armature and contact of a relay 99 to the negative pole of the battery 95. The negative pole of the battery 95 is also connected through the coil of a relay 99 and conductor 100 to the truck chassis, thereby providing an electrical connection between the negative pole of the battery and the pointer 92 through the pipe 12 and tank 11. With the pointer 92 out of engagement with the contact 93, the relay 99 is de-energized, causing engagement of the relay armature with its contact to close the energizing circuit for the valve 97 to maintain it open. Rotation of the magnet 91 produces corresponding rotation of the pointer 92 and engagement of the latter with the contact 93 closes the electrical circuit through the coil of relay 99 with consequent de-energization of the valve 96 to effect closing of the valve.

With the contents of the tank 11 at a low level, the pointer 92 is spaced from the contact 93. Upon introduction of liquid in the tank 11, rotation is effected of the shaft 88 through the medium of the float 90 to move the pointer 92 toward the contact 93 to eventually produce engagement therebetween upon attainment of a predetermined liquid level in the tank. The engagement of the pointer 92 with the contact 93 closes the circuit as previously described to close the magnetic valve 97 and interrupt flow to the tank.

The arrangement above described also serves as a liquid level indicator as the pointer 92 is visible from the exterior of the tank. By means of a dial, the amount of liquid in the tank at any time can be determined by reference to the position of the pointer 92 with respect to the dial.

The temperature maintained within the tank 55 may be regulated by manual adjustment of the back pressure control valve 32. Also, means are provided for controlling the temperature within the body either in conjunction with or independently of the valve 32 by use of a temperature-responsive element arranged within the insulated body. For this purpose, a by-pass 101 is provided around the valves 32a and 32. A pipe 102 controlled by a manually-operated valve 103 leads from the pipe 29 to the by-pass 101 from a point in the pipe 29 between the valves 32 and 100. A magnetic valve 104 is located in that section of the by-pass 101 upstream of the point of connection of the pipe 102 to the by-pass and a manually-operated valve 105 is provided in the remaining section of the by-pass 101. One terminal of the valve 103 is connected to the positive pole of a battery 106 while the remaining terminal of the magnetic valve is connected to the negative pole of the battery 106 through a thermostat 107 arranged in the body 10. A man-

ually-operated switch 108 is provided in the electrical circuit just described. The valve is closed upon de-energization and opens upon energization. The thermostat is closed at high temperatures and opens at lower temperatures.

With the valves 103 and 105 closed and the valve 100 open, vapor flows from the tank 11 to the tank 25 through the back pressure control valve 32 which under these circumstances is the sole temperature regulator for the body. With the valves 32a and 103 closed and the valve 105 open, vapor flows from the tank 11 to the tank 25 through the valve 104 and the temperature in the body is regulated solely by the thermostat 107. With the valves 32a and 105 closed, and the valve 103 open, vapor from the tank 11 flows successively through the valves 104 and 32 to the tank 25 and the temperature in the body is under the joint control of the two regulating means. When the by-pass is closed, the switch 108 may be opened, thereby avoiding all possibility of unnecessary drainage of the battery 106 should the thermostat 107 close during a period of non-operation of the refrigeration system.

I claim:

1. A mobile refrigerated transportation unit comprising a chassis, an insulated body mounted on said chassis, an absorption refrigeration system evaporator mounted within the insulated body and consisting of a storage tank mounted adjacent the top of said body and two sets of vertically disposed coils connected thereto, a partition extending between said coils and dividing the insulated body into separated compartments with one of said coils in each compartment, and an absorber connected to said evaporator.

2. A mobile refrigerated transportation unit according to claim 1 characterized by the absorber being mounted upon the chassis outside said insulated body.

3. A mobile refrigerated transportation unit comprising a chassis, an insulated body mounted thereon, an absorption refrigeration system evaporator mounted within said body and consisting of a refrigerant storage tank inside and adjacent the top of said body and refrigerant evaporator coils connected to said tank and also supported within said body, an absorber mounted on the chassis, a pipe leading from the tank to the absorber for the passage of refrigeration vapors, a second pipe leading to the storage tank for filling the same with refrigerant, a third pipe leading to the absorber whereby the same may be filled with or emptied of absorbent, detachable means for connecting said second and third pipes to appropriate storage tanks, and valves for controlling flow through said last-named pipes to the first-named storage tank and the absorber respectively.

4. A mobile refrigerated transportation unit comprising a chassis, an insulated body mounted thereon, an absorption refrigeration system evaporator including a tank and evaporating coils within said body, a first absorber and a second absorber mounted on said chassis, a first

pipe leading from the top of said tank to the bottom of said first absorber, a second pipe leading from the top of said first absorber to the bottom of said second absorber, a third pipe communicating with the bottom of said first absorber, a back pressure regulating valve in said first pipe, a fourth pipe leading to the top of said second absorber from said first pipe at a point between said back pressure regulating valve and said tank, and a manually operated valve in said fourth pipe.

5. An absorption refrigeration system comprising an evaporator, a first and a second absorbent tank, a first hollow casing in said first tank having a discharge nozzle, a first pipe leading from the evaporator to said first casing, a first tube fitting over said first casing nozzle in fluid-tight relation thereto and having a port beyond the end of said nozzle, a second hollow casing in said second absorber and having a discharge nozzle, a second pipe leading from an elevated point in said first tank to said second casing, a second tube fitting said second casing nozzle in fluid-tight relation and having a port beyond the end of said nozzle, a passageway providing communication between the interior of said second casing and said second tank, and a check valve in said passageway permitting only flow into said second casing.

6. An absorption refrigeration system according to claim 5 characterized by a back pressure regulating valve in said first pipe, a third pipe leading to said second tank from said first pipe at a point between said back pressure regulating valve and said evaporator, and a manually actuated valve controlling flow through said third pipe.
